UNITED STATES PATENT OFFICE

JOHN W. WILSON, OF CHICAGO, ILLINOIS, ASSIGNOR TO LINK-BELT COMPANY, OF CHICAGO, ILLINOIS, A CORPORATION OF ILLINOIS

CONVEYER-TROUGH DRIVING CONNECTION

Application filed December 29, 1928. Serial No. 329,267.

My invention relates to a device for use with conveying machinery and has particular reference to a shaker or reciprocating type of conveyor wherein the material delivered to the conveyor trough, for example by a feeder, is conveyed rearwardly away from the feeder by a longitudinal reciprocation of the trough. One object of my invention is to provide an improved connecting element between the driving unit and the trough. Another object is to provide means for distributing, dividing or reducing the strain incidental to driving the conveyor. Another object is the provision of driving means for the trough which shall be placed laterally or vertically, or both laterally and vertically, out of line of movement of the trough. Another object is the provision of improved connecting means between such trough and a correctly aligned or misaligned driving means. Other objects will appear from time to time in the course of the specification and claims.

My invention is illustrated more or less diagrammatically in the accompanying drawings, wherein—

Figure 1 is a plan view;

Figure 2 is a side elevation;

Figure 3 is an inverted partial plan view on an enlarged scale;

Figure 4 is a section on the line 4—4 of Figure 3;

Figure 5 is a section on the line 5—5 of Figure 1;

Figure 6 is a partial plan view on an enlarged scale of a modified form;

Figure 7 is a side elevation illustrating a further variation of my device;

Figure 8 is a plan view of the device shown in Figure 7, and

Figure 9 is a further variant form.

Like parts are indicated by like symbols throughout the specification and drawings.

Whereas I do not wish to limit myself to the particular structure of employment herein shown, except so far as limited thereto by the language of my claims, my invention is herein illustrated as applied to a reciprocating conveyor such as is used in conveying coal in a coal mine. Referring, for example, to

Figure 2, A indicates the floor and A¹ the roof.

B generally indicates a conveyor trough which may be mounted for reciprocation for example upon the rollers B¹, which rest upon track members B² and support the upper track members B³ upon the trough B. The trough is herein shown as made in a number of sections, it being understood that the length of the trough may be increased or diminished at need.

C diagrammatically indicates any suitable reciprocating means for said trough, said reciprocating means including the crank arms C¹ C². It will be understood that any suitable trough is employed to which an oscillation is imparted by said crank arms C¹. C² generally indicates a driving yoke having the two arms C³ C⁴, each such arm being pivoted at its outer end to the outer end of one of the cranks C¹. The yoke C² is provided with a lateral extension C⁴, which terminates in a sleeve C⁵. Mounted in said sleeve C⁵, the interior of which is provided with the cylindrical bore C⁶, is the swivel pin or member generally indicated in Figure 4 as D, with a cylindrical bearing member D¹ at each end thereof. Extending from one end of the swivel pin D is the screw-threaded extension D² provided with the lock and adjustment nuts D³. At the opposite end of the member D is the enlarged shoulder D⁴ and the extension D⁵ having upper and lower parallel bearing faces D⁶. D⁷ D⁸ indicate thrust washers, whereby rotation of the member D in relation to the sleeve C⁵ is permitted. D⁹ is held against rotation in relation to the member D by the pin D¹⁰.

E generally indicates a clevis which is pivoted for rotation about the horizontal bearing member E¹, such member being mounted upon any suitable depending lug or lugs E² upon a plate E³, herein shown as secured to the bottom of the trough B. E⁴ indicate strengthening webs. The clevis at its opposite end terminates in a vertically separated fork including the members E⁵ E⁶, the inner faces of which engage the opposed faces D⁶ on the extension D⁵ of the swivel member D. The members D⁵ and E⁵ are apertured in line

to receive the vertically pivoted pin G with its upper head G¹ and any suitable transverse locking means G², herein shown as a cotter pin. To prevent the pin from turning the head is cut away as at G³ to engage an opposed flat surface G⁴ upon the hub member E⁶.

Referring to the variant form shown in Figure 6, the sleeve C⁵ has slidably mounted in it the pin or shaft H headed as at H¹ and provided with the spring abutments or washers H². Compressed between the abutments H² and one side of the sleeve C⁵ is the spring or springs H³. The connection between the pin H and the trough B is the same as shown in Figures 1 and 2 and above described.

Referring to the form of Figures 7 and 8, the arms C¹ and the power unit extend upwardly instead of depending as shown in Figure 2. The yoke C², with its arms C³, is positioned sufficiently above the power unit to be shortened as shown in Figure 8. The connection between the hub or sleeve C⁵ and the pin D is the same as above described. However, in place of the short arm E I have substituted an extended rod I with the head I¹, the terminal portion I², the abutment washers I³ and the nuts I⁴ holding the assembly in position. Slidably mounted on the portion I² is the yoke I⁵, which is centered between the springs I⁶ I⁷, thus allowing a certain amount of yielding to the yoke I⁵ along the shaft I² which serves to cushion the conveying action exerted by the power plant C upon the trough B. The arms I⁸ of the yoke I⁵ are forked as at I⁹ to receive the upwardly extending members I¹⁰ mounted on the trough B, through which the conveying movement is imparted to the trough.

Figure 9 illustrates a device which varies from the device of Figures 7 and 8 in that, in place of the springs I⁶ I⁷, are inserted yielding members I¹¹ I¹², which may be for example of rubber.

It will be realized that whereas I have described and shown an operative device, many changes may be made in the size, shape, relation and distribution of parts without departing from the spirit of my invention, and I wish, therefore, that my showing be considered in a large measure as diagrammatic.

The use and operation of my invention are as follows:

In setting up reciprocating conveyors, for example for mine use, on the bottom of mine entries and the like, it is difficult to obtain an accurate alignment of working parts.

An important feature of my invention is the provision of a universal or flexible connection between the driving means and the trough B of such a conveyor. I may obtain this connection by employing the longitudinal swivel pin generally indicated as D, and shown in Figures 1 and following. The pin

D is swiveled into the cylindrical terminal hub or sleeve C⁵ of the yoke extension C⁴. Thus the drive to which the trough is connected may rotate about a longitudinal axis without throwing any strain upon the yoke and without displacing or throwing additional wear upon any of the driving parts. I do not wish to be limited, except so far as set out in the claims, to any particular connection or spacial relation between the driving unit and the trough. A practical solution of the problem is to position the power plant to one side of the axis of the trough and in such case I provide a universal connection between the lateral extension of the yoke C² and the trough. Regardless of the location of the driving means I prefer to interpose some variety of highly flexible or universal driving connection, as shown herein. I may instance the vertical pivot pin G which connects the end of the swivel pin to the clevis E which, in turn, is pivoted about the horizontal axis E¹. The result is a peculiarly flexible and efficient driving connection which permits the assembly and its various parts to adjust themselves and to perform their functions without being affected by slight irregularities in movement or in position of the driving means or trough. The thrust washers D⁷ and D⁸ permit rotation of the member D in relation to the member C⁵. Owing to the flexible connection, a rigid alignment of the driving means in relation to the trough is unnecessary.

Referring to Figures 6 and following I illustrate shock taking means in the line of drive. In Figure 6 I show a yielding connection between the sleeve C⁵ and the pin or shaft H. This cushions shocks and provides an improved connection to the trough and minimizes wear on the driving connection and on the power plant. Figures 7 and 8, in which I show the driving connection above rather than below the trough, I interpose a yielding connection between the yoke I⁵ and the driving member I. This yielding connection may be provided by the springs I⁶ I⁷ or by the yielding blocks I¹¹ I¹² of Figure 9.

I claim:

1. In a reciprocating conveyor, a conveyor trough, driving means adapted to impart to it a conveying reciprocation, and a driving connection intermediate said driving means and said trough, including means permitting movement or misalignment of said trough or drive about horizontal and vertical axes.

2. In a reciprocating conveyor, a conveyor trough, driving means adapted to impart to it a conveying reciprocation, and a driving connection intermediate said driving means and said trough, said driving connection including longitudinal pivoting means, vertical pivoting means and transverse pivoting means.

3. In a reciprocating conveyor, a conveyor trough, driving means adapted to impart to it a conveying reciprocation, and a driving connection intermediate said driving means and said trough, including means permitting vertical, horizontal or lateral movement or misalignment of said trough or drive.
4. In a reciprocating conveyor, a conveyor trough, driving means positioned adjacent said trough, adapted to impart to it a conveying reciprocation, said driving means including a plurality of crank arms, and a driving connection intermediate said crank arms and said trough, including a yoke, an arm on said yoke pivoted to each of said crank arms and a lateral extension from said yoke, a connection between said lateral extension and the trough, including a swivel pin rotatable in relation to said lateral extension and about a longitudinal axis, a clevis pivoted to said trough for rotation about a transverse horizontal axis and a vertical rotatable connection between said swivel pin and clevis.
5. In a reciprocating conveyor, a conveyor trough, driving means adapted to impart to it a conveying reciprocation, and a driving connection intermediate said driving means and said trough, said driving connection including a swivel pin rotatable about a longitudinal axis, a clevis pivoted to said trough for rotation about a transverse horizontal axis, and a vertical rotatable connection between said swivel pin and clevis.
6. In a reciprocating conveyor, a conveyor trough, driving means adapted to impart to it a conveying reciprocation, and a driving connection intermediate said driving means and said trough, said driving connection including a yoke operatively connected to said driving means, and a flexible connection between said yoke and trough, said connection including plural angularly disposed pivots permitting relative displacement of the trough and drive means.
7. In a reciprocating conveyor including a reciprocable conveying trough and power drive means therefor, a driving connection between the power means and trough to impart conveying movement to the trough, said driving connection including means permitting lateral, horizontal or vertical relative movement or displacement of the trough, and power means to compensate for irregularities in the surface on which said members are supported.

Signed at Chicago, county of Cook and State of Illinois, this 17th day of November, 1928.

JOHN W. WILSON.
